INVENTOR
CHARLES HARTER

BY
T. B. Cornwall. PITT.

UNITED STATES PATENT OFFICE.

CHARLES HARTER, OF ST. LOUIS, MISSOURI.

SIDE-DOOR POST FOR CARS.

1,210,067.

Specification of Letters Patent. Patented Dec. 26, 1916.

Application filed July 3, 1916. Serial No. 107,287.

To all whom it may concern:

Be it known that I, CHARLES HARTER, a citizen of the United States, residing at St. Louis, Missouri, have invented a certain new and useful Improvement in Side-Door Posts for Cars, of which the following is a full, clear, and exact description, such as will enable others skilled in the art to which it appertains to make and use the same, reference being had to the accompanying drawings, forming part of this specification.

My invention relates generally to railway cars and more particularly to a movable door post which coöperates with the sliding doors which normally close the side door opening of a box car.

It will be understood that the side door opening of a box car is generally of a fixed or standard width and while such opening is of sufficient width for ordinary purposes, it will not admit the loading of objects of unusual size, such as motor vehicles, trucks, or extra large machines which are necessarily shipped in assembled form, and to overcome these objections I propose to construct a box car with an extra wide side door opening; to utilize two sliding doors for normally closing said opening and combine with the car and doors a movable door post which is positioned between the doors and which serves as a reinforcing or strengthening member between the side sill and side plate of the car body at a point near the center of the side door opening.

The principal objects of my invention are, to provide a comparatively simple door post for the side door opening of a box car which post is mounted for sliding movement in either direction independently of the doors which coöperate with said post and close the opening; to provide simple means for effectively locking both ends of the post to the car body so that when properly positioned, said post forms a brace and strengthening member near the center of the side door opening; to provide simple means for effecting a ready release of the means which connects and locks the ends of the post to the car body; and to construct the post locking means so that it will automatically shift into locking position when the post is returned to its normal position.

With the foregoing and other objects in view, my invention consists in certain novel features of construction and arrangement of parts, hereinafter more fully described,

claimed and illustrated in the accompanying drawings, in which—

Figure 1 is an elevational view of a portion of the side of a box car having a side door opening of extra width, said car being equipped with a door post of my improved construction. Fig. 2 is a horizontal section taken approximately on the line 2—2 of Fig. 1. Fig. 3 is an enlarged horizontal section taken approximately on the line 3—3 of Fig. 1. Fig. 4 is a vertical section taken approximately on the line 4—4 of Fig. 3. Fig. 5 is an enlarged vertical section taken approximately on the line 5—5 of Fig. 1. Fig. 6 is a vertical section taken approximately on the line 6—6 of Fig. 5. Figs. 7 and 8 are detail sectional views showing the locking means at the upper end of the door post in different positions. Fig. 9 is a detail section of the side post of the car body and showing the supporting rails upon which the post travels during its movement across the door opening. Fig. 10 is a horizontal section taken approximately on the line 10—10 of Fig. 6.

Referring by numerals to the accompanying drawings, 10 designates the side sill of a car, 11 the side plate and 12 the usual side wall, which latter is provided with an extra wide door opening, the same being normally closed by a main door 13 and an auxiliary door 14, both of which doors are of ordinary construction and of the sliding type inasmuch as they are provided at their upper ends with the usual hangers 14^a, the rollers of which operate on rails 15 secured to the car body above the door opening.

Fixed to the underside of the plate 11 and at a point where the edges of the doors 13 and 14 meet is a block 16, preferably cast and provided in its lower outer corners with recesses 17, the same being separated by a transversely disposed centrally arranged wall 18.

Fixed in any suitable manner to the side sill 10 at a point immediately beneath block 16 is a block 19 preferably cast, and provided in its upper outer corners with notches or recesses 20, the same being separated by a centrally arranged transversely disposed wall 21.

The post 22 contemplated by my invention may be formed of either wood or metal, and fixed to the upper end thereof in any suitable manner is a hanger casting 23, the same being provided with upwardly pro-

jecting inner and outer legs 24 and 25 respectively. Journaled at the ends of the inner leg 24 are rollers 26 which bear on a track rail 27, preferably an angle, which is fixed in any suitable manner to the sides of plate 11 immediately over the door opening. Formed integral with or fixed to the upper portion of outer leg 25 is an inwardly projecting hook or flange 28 which engages over the horizontal flange of a rail 29, preferably in the form of an angle which is fixed in any suitable manner to the plate 11 immediately above the door opening.

The means for locking the upper end of the post to block 16 is located in the space between the lower portions of legs 24 and 25, said means comprising a comparatively long jaw 30 and a comparatively short jaw 31, both of said jaws being provided with trunnions 32 and 33 respectively which occupy the same horizontal plane and are journaled in legs 24 and 25. These jaws are spaced apart and when in vertical or locking position, their upper portions occupy the notches or recesses 17 on opposite sides of the wall 18. (See Fig. 6.)

Pivotedly connected to the lower portion of the shorter jaw 31 a short distance from the axis thereof is one end of a link 34, the opposite end of which is pivotedly connected to the lower end of jaw 30. The lower portion of short jaw 31 is provided with a depending lug 35 which is adapted to be engaged by a hook 36, which latter is formed on the end of a latching member 37, the same being provided with trunnions which are journaled in legs 24 and 25.

Pivotedly connected to the outer end of the latching hook 37 is the upper end of an operating rod 38, the same extending downward through suitable bearings on the side of post 22, the lower end of said rod being provided with an operating handle 39.

The means for locking the lower end of the post to block 19 is practically the same as the locking means just described; said lower locking means comprising comparatively short and long locking jaws 40 and 41, the same being provided with suitable trunnions which are journaled in the walls of a housing 42, the same being preferably cast and fixed to the lower end of post 22 in any suitable manner. When these last mentioned jaws are in vertical or locking position, their lower ends occupy the notches or recesses 20 in block 19 on opposite sides of the wall 21.

The upper end of jaw 40 is connected to the upper end of jaw 41 by a link 43, and the upper end of said jaw 40 is provided with a lug 44 which is adapted to be engaged by a hook 45, the same being formed on the inner end of a latching member 46 which is journaled to the walls of member 42.

65 Fixed to post 22 on the outer face thereof

is a vertically disposed strip 47, the same serving as a stop against which the inner edges of the doors 13 and 14 engage when said doors are closed.

Any suitable means can be utilized as an inside latch for securing the auxiliary door 14 to the post when said door is in closed position. A simple form of latch is illustrated in Figs. 3 and 4, said latching means comprising a hook 48 which is pivotally mounted on the door post and projecting toward the side which engages the free edge of the auxiliary door. This hook is adapted to engage behind a lug 49, the same projecting inwardly from a plate 50, the latter being fixed to the inside of door 14 adjacent to the inner edge thereof. Under ordinary conditions or where only the main door 13 is in use, the door post 22 occupying a position at the inner edge of auxiliary door 14 and locked thereto, and to the car body above and below the door opening, serves as the door post against which the free edge of main door 13 engages when the latter is closed. It will be understood that when in locked position, the upper ends of jaws 30 and 31 occupy the recesses 17 and with hook 36 engaging the lug 35 on the lower end of jaw 31, the parts are held in locking position. Likewise, the lower end of the post 95 is locked to block 19 by the engagement of the lower ends of jaws 40 and 41 in the recesses 20, and said jaws are held in such locking position by the engagement of hook 45 with the lug 44 on the end of jaw 40.

When it is desired to provide the wide door opening for the purpose of loading or unloading extra large objects, the main door 13 is moved away from post 22 to full open position, after which the latching means between the auxiliary door and post 22 is released, thus permitting said auxiliary door to be moved away from the post to full open position. The post is now unlocked or disconnected from the car body by raising rod 38 and simultaneously depressing the outer end of latching member 46. These operations disconnect hooks 36 and 45 from the lugs on the ends of short jaws 31 and 41, and the post is now moved toward the edge 115 of auxiliary door 14, during which movement the rollers 26 ride upon track 27 and the rollers on hangers 14 travel in the usual manner upon rail 15. As the post moves away from blocks 16 and 19, the transverse walls 18 and 21 will bear against the inner faces of the short jaws 31 and 40, thereby swinging said jaws upon their fulcrums into substantially horizontal positions. The movements thus imparted to the short jaws 125 is transmitted by links 34 and 43 to long jaws 30 and 41, but owing to the distance between the points where the links are pivoted to said jaws and the trunnions of said jaws, the latter will only be shifted 13

a slight distance and the movement will be such that their free ends will be moved toward the short jaws. Thus, the jaws in moving away from the blocks 16 and 19, are 5 set or shifted into position so that they will automatically return to locking positions when the post is returned to its normal position.

By making the door post separate and independent of both doors it can be maintained in normal position while both doors are open and when so positioned it serves as a reinforcing and strengthening member between the side sill and top plate of 15 the car frame and at a point intermediate the door posts which latter are necessarily spaced a considerable distance apart to provide the extra wide door opening. Further, when the door 13 is opened the post 22 20 serves as a door post against which the inner edge of the auxiliary door 14 engages and as said post is rigidly fixed at both ends to parts of the car frame, the free edge of said auxiliary door has a firm and 25 substantial support and consequently there will be less tendency to unseat or detach the auxiliary door from the car body than where its free edge is unprotected and devoid of a substantial support and bearing.

30 If desired, the post can be retained in its normal position and both doors opened, thus forming practically two openings, one of which can be used as an entrance and the other as an exit for workmen engaged in 35 loading or unloading the car. With both doors in full open position and the post positioned at the edge of auxiliary door 14, the full width of the door opening can be utilized in loading or unloading extra large 40 objects, such as automobiles, trucks, large assembled machines, etc. When the post is returned to its normal position, the lugs 33 and 44 on the ends of the short jaws 31 and 45 40 will engage against the inner ends of the walls 18 and 21, thereby partially restoring the shorter jaws to their normal vertical positions, and as the free ends of the longer jaws 30 and 41 engage against the walls 18 and 21, both ends of jaws will be shifted to 50 their normal vertical or locking positions, with the free ends of said jaws positioned in the recesses 17 and 20. As the shorter jaws return to their normal or locking positions, the lugs 33 and 44 on the inner ends 55 of said jaws will be reengaged by the hooks 26 and 45 with the result that said jaws will be maintained or held in locking position.

60 By my improved construction a car having an extra wide side door opening is provided, which wide opening can be utilized when desired, or under ordinary conditions or where comparatively small objects are to be loaded or unloaded, the auxiliary door and door post can remain in closed positions and 65 the main door utilized in the usual manner.

The post cannot be detached from the car body and, therefore, it cannot be lost or mislaid and when the post is in normal position it serves as a support and bearing for the inner edges of the doors, in addition to 70 serving as a reinforcing and strengthening member between the side sill and side plate of the car body, and at a point near the center of the comparatively wide door opening. The ends of the post can be readily disconnected from the car framing; likewise said post can be readily disconnected from the auxiliary door, and when the post is returned to its normal position, the locking means carried by said post automatically 75 80 engages with the anchoring members which are fixed to the car frame.

It will be readily understood that minor changes in the size, form and construction of the various parts of my improved side door post can be made and substituted for those herein shown and described, without departing from the spirit of my invention, the scope of which is set forth in the appended claims.

I claim:

1. A car provided with a door opening, a post spanning said opening and having sliding connection with a portion of the car body, socket blocks on the car body above and below the door opening, and a pair of jaws pivotally mounted on each end of the post which jaws are adapted to engage the socket blocks to lock the post to the car body.

2. A car provided with a door opening, a post spanning said opening and having sliding connection with a portion of the car body, socket blocks on the car body above and below the door opening, a pair of jaws pivotally mounted on each end of the post which jaws are adapted to engage the socket blocks to lock the post to the car body, and a latching member adapted to engage one of the jaws of each pair to hold the same in locked position.

3. A car provided with a door opening, a post spanning said opening and having sliding connection with a portion of the car body, a pair of pivotally mounted jaws on each end of the post, the members of each pair of jaws being connected so as to operate simultaneously, and means on the car body above and below the door opening for receiving the outer ends of said jaws and to cooperate therewith to hold the post in locked position.

4. A car provided with a door opening, a pair of sliding doors adapted to normally close said opening, a post spanning said opening and having sliding connection with the car body independently of said doors, pivotally mounted jaws on each end of the post, means on the car body above and below the door opening for receiving the outer ends of said jaws to maintain the post in po-

sition between the sliding doors, and readily releasable latching means for securing said post to one of said doors.

5. A car provided with a door opening, a post spanning said opening and having sliding connection with a portion of the car body, blocks above and below the door opening, each of which blocks is provided with a pair of recesses, and a pair of locking 10 jaws pivotally mounted on each end of the

post, the outer ends of which jaws are adapted to engage in the recesses of the blocks to hold the post locked to the car body.

In testimony whereof I hereunto affix my signature in the presence of two witnesses, 15 this 30th day of June, 1916.

CHARLES HARTER.
